Atty.

UNITED STATES PATENT OFFICE.

GEORGE M. DAVIS, OF BURRITT, ILLINOIS.

CAP FOR VEHICLE-POLES.

SPECIFICATION forming part of Letters Patent No. 714,678, dated December 2, 1902.

Application filed October 10, 1902. Serial No. 126,680. (No model.)

To all whom it may concern:

Be it known that I, GEORGE M. DAVIS, a citizen of the United States of America, residing at Burritt, in the county of Winnebago and State of Illinois, have invented certain new and useful Improvements in Caps for Vehicle-Poles, of which the following is a specification.

My invention relates to caps for vehicle-
poles provided with means for connecting the
central ring of a neck-yoke therewith. Its
object is to provide means for connecting the
ring of a neck-yoke with a vehicle-pole se-
curely and in such manner that driving-reins
cannot pass under or become entangled with
the front end of such pole; and it consists of
a certain new and useful device especially
contrived therefor, all as hereinafter fully
described, and specifically pointed out in the
claim hereof.

Referring to the accompanying drawings,
which form a part of this specification, Figure 1 is a side view of the front end of a ve-
hicle-pole provided with my improvement
and operatively connected with the ring of a
neck-yoke. Fig. 2 is a front end view of the
same.

Like letters of reference indicate cor-
sponding parts in the two views.

A is a ferrule forming the body of the pole-
cap, which is provided with a downwardly-
projecting lug A' and an upwardly-projecting
lug A² to engage the lower and upper por-
tions, respectively, of a neck-yoke ring and
having backwardly-projecting attaching-arms
A³, for securing the ferrule A to the pole and
a forwardly-extending loop A⁴, for connecting

such cap with a single or double tree, when de-
sired.

B is a vehicle-pole inserted and secured 40
into the ferrule A of the pole-cap.

C is a neck-yoke ring operatively connect-
ed with the pole-cap.

D is a neck-yoke with its ends broken away.

The attaching-arms A³ securely connect 45
the pole-cap with the pole B. Since the front
end of the pole B when connected with the
neck-yoke ring C in the manner shown does
not project beyond the neck-yoke, driving-
reins cannot pass under or become entangled 50
therewith.

What I claim as new, and desire to secure
by Letters Patent, is—

As a new unitary article of manufacture,
the pole-cap comprising the ferrule A, pro-
vided with a downwardly-projecting lug A'
and an upwardly-projecting lug A², for en-
gaging the upper and lower portions, respec-
tively, of a neck-yoke ring, and having back-
wardly-projecting attaching-arms A³, for se-
curing the ferrule of the cap to a pole, and a
forwardly-extending loop A⁴, for retaining
the neck-yoke ring C in position on the pole-
cap and connecting such cap with a single or
double tree, substantially as and for the pur- 65
pose set forth.

In testimony whereof I have signed my
name to this specification in the presence of
two subscribing witnesses.

GEORGE M. DAVIS.
